Primary Examiner — Jae Liang*Assistant Examiner* — Tia Ruth-Renee Polidori(74) *Attorney, Agent, or Firm* — Preston P. Frischknecht;
Project CIP(57) **CLAIM**

The ornamental design for a container with lid, as shown and described.

DESCRIPTION

FIG. 1 is a first perspective view of the container with lid;

FIG. 2 is a first side view thereof;

FIG. 3 is a second side view thereof;

FIG. 4 is a third side view thereof;

FIG. 5 is a fourth side thereof;

FIG. 6 is a top view thereof;

FIG. 7 is a bottom view thereof; and,

FIG. 8 is a perspective view showing the container with lid in an alternate position.

The dashed lines depict portions of the container with lid that form no part of the claimed design.

1 Claim, 8 Drawing Sheets(56)
